UNITED STATES PATENT OFFICE.

ENOCHE PROUTY, OF DETROIT, MICHIGAN.

COPYHOLDER.

Application filed July 29, 1922. Serial No. 578,355.

This invention relates to an improvement in copy holders, and particularly to such a device intended for use with a typewriter.

An object is to provide a copy-holder which can be set in the rear of a typewriter to thus be conveniently located, and which is held in position and held against shifting and vibration by engagement of the machine therewith.

10 A further object resides in providing a brace or rest by which the copy-holder is supported in the upright relation, and in mounting the rest to be folded when the holder is to be packed or carried.

15 Another object is to provide a line guide and shifting mechanism which can be actuated with great facility by the operator.

A still further object lies in so constructing the line guide that this element is positively held and stopped in the proper positions when in use.

With these and other objects in view, which will be apparent to those skilled in the art, my invention includes certain novel 25 features of construction and combinations of parts which will now be set forth.

In the drawings:

Figure 1 is a front elevation.

Fig. 2 is a view in edge elevation.

30 Fig. 3 is a rear elevation.

Fig. 4 is a fragmentary detail to better show the line guide head.

Fig. 5 is a similar view of the actuating lever.

35 Fig. 6 shows the line guide pawl in perspective.

The easel or rest 1, which is of sheet metal or other suitable material, has a base flange 2 bent forwardly and is provided at one 40 edge with a rearwardly bent flange 3. The base flange is adapted to lie flat upon the table or stand supporting the typewriter, and the easel is disposed at the proper angle to hold the copy in full and easy view of the operator.

45 The feet of the typewriter can be placed to rest upon the flange and thus hold the easel in the upright relation, but it is desirable that other means be provided to support the same. On the rear of the easel I mount the bearings 4 and 5, and a supporting bracket 6 is mounted in these bearings, the foot 7 of this bracket being swung out when in use to rest upon the surface receiving the base flange 2, and thus supporting and steadyng the easel. When the copy

holder is to be packed or carried, the supporting bracket can be swung to bring the foot flat against the back of the easel.

Bearing 4 is extended laterally at one side 60 as at 8, and a spring arm 9 is secured in an opening formed in this extension, to thus be rigidly mounted. The spring arm extends laterally and then upwardly in the rear of the easel, and at its upper end is bent over 65 to extend through a slot 10 in the upper edge of the easel. On the forward side of the easel the arm is bent laterally to form a gripping arm 11, and a rubber or other sleeve 12 is fitted on this arm to give the 70 proper friction grip against a note book or copy sheet placed between the arm 11 and easel 1.

A bar 13, secured on the flange 3, is provided at its upper and lower ends with bearing arms 14 and 15 having aligned bearing 75 openings formed therethrough, and a line guide supporting rod 16 is slidably mounted in these openings. A line-guide pawl 17, best shown in Fig. 6, is provided with an 80 opening 18 at one end to loosely receive the rod 16; and at its remaining end this pawl is notched at one side at 19 to fit over the bar 13. The notch 19 is formed to provide gripping edges 20 and 21 positioned to grip 85 against the forward and back faces of the bar when the pawl has its remaining end tilted upwardly.

The line guide consists of an indicator arm 22 and a head 23 mounted slidably on 90 the supporting rod 16, the head supporting the arm in a horizontal position on the forward side of the easel or rest 1. The head 23 is provided with a slot 24 to receive that end of pawl 17 which is fitted on the supporting rod 16, and this slot is widened on the rear side to allow rocking movement of the pawl. An extension 25 on the head has a bore therein extending to the opening receiving the rod 16, and a coiled spring 26 100 having light pressure is fitted in the bore and is held in place by screw 27 to bear frictionally against rod 16. This spring holds the line guide structure against sliding down the rod due to its own weight.

105 The lower end of bar 13 is cut away or recessed as at 28, adjacent the flange 3 to provide a bearing face and the shift lever 29 loosely mounted on supporting rod 16, has a wedge-shaped bearing member 30 110 which is in contact with this face. The lower end of rod 16 is threaded and a nut

31 is turned onto this end to retain the lever in place and form a fulcrum for the same. A coiled spring 32 is fitted on the rod to bear at its lower end against the arm 15, and 5 a split collar 33 is clamped on the rod as a bearing for the upper end of the spring.

In use, the copy holder is placed with the base flange 2, and the rest-foot 7 on the typewriter desk or table, and the machine can 10 be set with its rear legs resting on the flange. The easel or rest is thus conveniently located for the operator, and the operating lever is disposed to be readily accessible for manipulation to shift the line guide. As 15 this lever is actuated the rear end drops when the front end is pressed, thus overcoming any unusual slant which might cause the finger-nail of the operator to engage the metal and be broken or bruised causing pain 20 and soreness. When the lever is pressed down the supporting rod 16 is drawn down against the resilient pressure of spring 32, and as the spring 26 holds frictionally 25 against rod 16 and the pawl is free for movement downwardly on bar 13, the line guide is moved down for the desired distance to uncover the next line on the copy sheet or notebook. When the lever is released the rod 16 is raised by the pressure of spring 30 32, and as the edges 20 and 21 of the pawl 17 engage against the bar 13 the line guide is held against upward movement. The rod slides against spring 26 when forced up by 35 spring 32, but the frictional bearing of this spring 26 is sufficient to hold the line guide against falling by gravity.

While in the foregoing I have shown and described only one specific embodiment, it will be appreciated that changes and variation 40 can be resorted to in the construction and arrangement of parts, to suit varying conditions of use, in view of which I wish to be limited only to such points as may be set forth in the claims.

45 I claim:

1. A copy holder comprising an easel, a rod reciprocably mounted in an upright plane substantially parallel with the easel, a line guide slidably mounted on the rod and 50 extending across the face of the easel, means frictionally holding the line guide against gravity movement on the rod, and means to adjust the frictionally holding means, a pawl carried by the line guide to hold said 55 guide against movement as the rod is slid upwardly, and means by which the rod is moved.

2. A copy holder comprising an easel, a rod reciprocably mounted in an upright relation substantially parallel with the easel, 60 a line guide slidably mounted on the rod and extending across the face of the easel, a spring carried by the guide frictionally engaging with the rod to hold said guide against gravity movement, means to adjust 65 the frictional engagement of the spring, an operating lever by which the rod is manually slid down, a spring resiliently holding the rod normally raised, and a pawl carried by the line guide to hold said guide 70 against movement as the rod is moved upwardly.

3. A copy holder comprising an easel, a rod reciprocably mounted in an upright relation substantially parallel with the easel, 75 a line guide slidably mounted on the rod and extending across the face of the easel, a spring carried by the guide frictionally engaging with the rod to hold said guide against gravity movement, an operating lever by which the rod is manually slid down, 80 a spring resiliently holding the rod normally raised, a pawl carried by the line guide to hold said guide against movement as the rod is moved upwardly, a wedge-shaped 85 bearing on the operating lever, and a correspondingly shaped bearing portion on the easel with which the lever bearing engages.

4. A copy holder comprising an easel, a 90 bar carried by said easel having bearing arms at its upper and lower ends provided with aligned bearing openings, a rod mounted in said openings for reciprocating sliding movement, a line guide slidably mounted 95 on the rod and extending adjacent the face of the easel, an operating lever by which the rod is slid downwardly, a spring resiliently urging the rod upwardly, a pawl associated with the line guide engaging said 100 bar to hold said guide against movement as the rod is slid up, a spring frictionally engaging the rod to hold the guide to move with said rod when the lever is depressed, and means to adjust the frictional engagement of the spring.

5. A copy holder comprising an easel, line-guide structure carried by the easel, a line-guide operating lever, a wedge-shaped bearing on the operating lever, and a correspondingly-shaped bearing portion on the 110 easel.

In testimony whereof I hereunto affix my signature.

ENOCH PROUTY.
